ADVERTISING DEVICE

Charles M. Polatty, Greenwood, S. C.

Application April 3, 1934, Serial No. 718,843

4 Claims. (Cl. 46—40)

The present invention relates to a novel advertising device in the form of an animated mechanical figure and has for one of its important objects to provide, in a manner as hereinafter set forth, a device of this character wherein the arms, legs, head, etc. are caused to describe various movements and are driven from a single source of power.

Other objects of the invention are to provide an advertising device of the aforementioned character which will be highly attractive, comparatively simple in construction, strong, durable, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of an advertising device constructed in accordance with the present invention.

Figure 2 is a view partially in vertical section and partially in rear elevation of the invention.

Figure 3 is a view in vertical section through the invention.

Figure 4 is a horizontal sectional view, taken substantially on the line 4—4 of Figure 3.

Figure 5 is a detail view in side elevation of one of the legs.

Figure 6 is a detail view in perspective of the shaft which actuates the head.

Figure 7 is a detail view in perspective of the swinging rod on which one of the legs is mounted.

Figure 8 is a detail view in perspective of the shaft which supports the arms.

Figure 9 is a detail view in vertical section, taken substantially on the line 9—9 of Figure 2, looking in the direction indicated by the arrows.

Referring now to the drawings in detail, it will be seen that the embodiment of the invention which has been illustrated comprises a hollow body 1 of suitable material which constitutes a casing, said body being mounted on a support 2. Journaled transversely in the lower portion of the body 1 is a shaft 3 which is driven from an electric motor by a belt and pulley connection 5.

The reference numerals 6 and 7 designate generally legs which depend from the body 1. The leg 6 is hingedly connected to the body 1, as at 8, and includes upper and lower sections 9 and 10, respectively, which are hingedly connected, as at 11. Loosely mounted on one end portion of the shaft 3 is a disk 12 which includes a substantially

segmental hub portion 13. A pin 14 projects from the shaft 3 for engagement with the substantially segmental hub portion 13. A flexible cable 15 has one end connected off-center to the disk 12 and its other end connected to the rear of the lower section 10 of the leg 6.

Mounted transversely in the body 1 above the shaft 3 is a rod 16 upon which a rod 17 is journaled for swinging movement. The rod 17 extends through the bottom of the body 1 and the leg 7 is fixed thereon for swinging movement. The leg 7 is operable in an opening 18 which is provided therefor in the lower portion of the body 1 while an opening 19 is provided for the cable 15. The rod 17 is formed to provide a slot 20 (see Figure 7) for the reception of an off-center pin 21 which projects from a disk 22 fixed on the other end portion of the shaft 3. It will thus be seen that as the shaft rotates swinging movement will be imparted to the rod 17.

Journalized vertically in the body 1 is a shaft 23 to which the head 24 is fixed. Projecting from the shaft 23 is an arm 25 which is formed to provide a slot 26 (see Figure 6) for the reception of an angular extension 27 on the upper end of the rod 17. By this arrangement oscillating movement is imparted to the shaft 23.

Journalized transversely in an upper portion of the body 1 and projecting laterally beyond said body is a shaft 28 to the end portions of which 85 swinging arms 29 are fixed. Depending from an intermediate portion of the shaft 28 is an arm 30 which is engaged in the slot 26 of the arm 25 for actuating said shaft 28.

A stationary support 31 rises from the top of the body 1 into the head 24, the lower portion of said head being provided with an arcuate slot 32 (see Figure 4) which accommodates said support. A pair of eyes 33 is mounted on the support 31, said eyes being observable through openings 34 in the head 24. A bracket 35 is mounted for vertical sliding movement on the support 31 and fixed on said bracket are upper and lower teeth 36 and 37, respectively, which are observable through a mouth opening 38. As illustrated 95 to advantage in Figures 3 and 4 of the drawings, a pin 39 projects from the lower teeth 37 and rides on a cam 40 which is mounted in the lower portion of the head 24.

In operation, when the motor 4 is energized, 105 the shaft 3 is rotated and swinging movement is imparted to the leg 7. The leg 6 is caused to describe a stamping movement, the sections 9 and 10 thereof swinging on the hinges 8 and 11, as indicated in broken lines in Figure 5 of the draw- 110

- ings. When the pin 14 engages the substantially segmental hub 13 for actuating the disk 12 the leg 6 is elevated to raised position through the medium of the cable 15. This elevating movement of the leg 6 is comparatively slow. However, when the connection of the cable 15 with the disk 12 passes upper dead center the leg 6 falls rapidly to lowered or normal position by gravity, the disk 12 running ahead of the shaft 3. 5
- 10 As the rod 17 swings on its supporting rod 16, oscillating movement is imparted to the vertical shaft 23 upon which the head 24 is fixed. As the head 24 is thus oscillated the eyes 23, being stationary, appear to roll or move in the openings 15 34. As the head 24 oscillates, the teeth 36 and 37 are caused to rise and fall on the support 31. It may be well to here state that the bracket 35 is splined on the support 31 to retain the teeth against rotation with the cam 40. As the shaft 20 28 is oscillated through its connection with the vertical shaft 23 the arms 29 are raised and lowered. If desired, a sound reproducing apparatus in the form of a radio receiving set or a phonograph may be provided in the device in which case 25 a speaker would be mounted in the head 24 for emitting the sound through the mouth opening 38. It is believed that the many advantages of an advertising device constructed in accordance with the present invention will be readily understood, 30 and although a preferred embodiment of the invention is as illustrated and described, it is to be understood that changes in the details of construction and in the combination and arrangement of parts may be resorted to which will fall 35 within the scope of the invention as claimed.
- What is claimed is:—
1. An advertising device of the class described comprising a body, a shaft rotatably mounted in the body, a leg hingedly connected to the body, 40 means operatively connecting the leg to the shaft for actuation thereby, and means for actuating the shaft, said leg including hingedly connected upper and lower sections, the first-named means comprising a disk including a substantially segmental hub portion loosely mounted on the shaft, a cable having one end connected to the lower 45

- leg section and its other end connected off center to the disk, and a pin fixed on the shaft and engageable with the substantially segmental hub portion for actuating the leg in one direction. 80
2. An advertising device of the class described comprising a body, a shaft rotatably mounted in the body, means for actuating the shaft, a rod pivotally mounted, at an intermediate point, for swinging movement in the body, a leg fixed on one end portion of the rod, a vertical shaft rotatably mounted in the body, an arm extending from the vertical shaft and operatively engaged with the other end portion of the rod for operatively connecting said vertical shaft thereto, a head fixed on the vertical shaft, another shaft journaled transversely in the body, arms fixed on the third-named shaft for movement therewith, means operatively connecting the third-named shaft to the first-named arm for actuation thereby, and means operatively connecting the rod to 85 the first-named shaft for actuation thereby. 90
3. An advertising device of the class described comprising a body, a hollow head mounted for swinging movement on the body, means for actuating the head, a stationary support fixed on the body and rising therefrom in the head, teeth mounted for vertical movement on the support, and a cam fixed in the head and operatively connected with the teeth for raising and lowering said teeth, the head having an opening therein 95 exposing the teeth. 100
4. In combination, a hollow body, an upright, oscillating shaft mounted therein, means for oscillating said shaft, a hollow head fixed to said shaft to oscillate therewith and having a wall 110 with spaced openings therein and also having an arcuate slot, a stationary support carried in and by the body and extending through said arcuate slot into said hollow head, and a pair of spaced eyes mounted on said support opposite the spaced 115 openings in the wall of the hollow head, whereby when said head is oscillated the stationary eyes appear to move or roll in said spaced openings in the head wall. 120
